UNITED STATES PATENT OFFICE.

LEWIS A. MARCUS, OF NEW YORK, N. Y.

RECEPTABLE.

Application filed May 5, 1925. Serial No. 28,151.

This invention relates to improvements in receptacles and more particularly to metallic receptacles of that general character having a hinged closure and an interiorly disposed 5 movable secondary receptacle therein, with operating means whereby the secondary receptacle may be raised and the cover opened. Such types of receptacles are particularly adapted for use as trash and garbage containers, where it is undesirable to actually handle various parts, as well as receptacles for surgical instruments, disinfecting cabinets, and the like, where access to the instruments or materials is desired without the 10 necessity of manually raising the cover or opening the drawer thereof by direct contact.

It is therefore one of the objects of the present invention to provide a receptacle of 20 simple and practical construction which may easily be operated to open the same thereby to permit access to the interior.

A further object is to provide a strong and durable receptacle of the above general 25 character of sanitary construction and having relatively few parts which may be inexpensively manufactured and assembled.

Other objects will be in part obvious and in part hereinafter pointed out in connection with the accompanying sheet of drawings illustrating two of the various possible 30 embodiments of the present invention.

The invention accordingly consists in the features of construction, the combination of 35 parts, and in the unique relation of the various members and the relative proportioning and dispositioning thereof, all as more clearly outlined herein.

To enable others skilled in the art to fully 40 comprehend the underlying features thereof, in order that they may embody the same, by numerous modifications in structure and relation contemplated by this invention, drawings depicting a preferred form of the 45 invention have been annexed as part of this disclosure, and in such drawings like characters of reference indicate corresponding parts throughout all the views, of which—

Figure 1 is a sectional elevation of the receptacle in normal position as shown in full lines, and open position as shown by dotted lines.

Figure 2 is a sectional perspective view 55 showing the various parts in disassembled relation.

For convenience, the invention will be hereinafter described with relation to its application to a sanitary garbage or trash can, altho it is to be, of course, understood that the invention is equally applicable to sanitary trays for surgical instruments without material modification.

Referring now to the drawings in detail, 10 indicates the main outer receptacle which is preferably of galvanized sheet iron and of cylindrical construction, provided with a closure 11 hinged to receptacle 10 in any desired manner, as indicated at 12. The lower portion of this receptacle is provided with a reinforcing bridge member 13, which includes a relatively flat upper supporting surface and two downwardly extending end portions 14 riveted or otherwise suitably secured to the receptacle 10. One end of this bridge may be slightly cut away, together with the outer wall of the receptacle 10, to provide an opening 15 in which a pivoted lever 16 is adapted to be inserted. This lever is supported by a pivot pin 17 associated with the downwardly extending end 14 of the bridge member 13. In order to form a durable and more substantial construction, this lever 16 has one end bent at right angles to provide a pedal or foot engaging member 18, while the opposite end is apertured as at 20 for the reception of a bolt 21 for securing the end 22 of a T-shaped member thereto, which member projects through slot 19 of the bridge 13. The cross part 23 of this member normally rests on the upper surface of the bridge member 13 and is adapted to engage the bottom 24 of an inner or auxiliary receptacle or bucket indicated at 25, which is normally supported on the bridge member 13. This inner receptacle or bucket may be provided with a handle 26, pivotally mounted on diametrically opposite lugs 27, the handle normally resting upon an inwardly extending flange portion 28.

It will be noted that the cover 11 engages the top of the outer receptacle 10 throughout the entire circumference. The bucket or inner receptacle 25 is preferably slightly higher than the outer receptacle, thereby to also engage the under side of the cover 11, thus making a double closure at the lines of contact between the closure and both receptacles which renders the receptacle more sanitary and further eliminates the possibility of ants 100 105 110

or flies getting into the interior of the bucket when the device is used as a garbage can.

A further purpose of the construction, as herein outlined, is to permit the opening and closing of the receptacle with the minimum amount of trouble and without the necessity of handling any of the parts. All that is necessary to effect this operation is for the operator to depress the pedal 18 with his foot, which causes the T-shaped member 22 and 23 to raise the bucket 25 to its dotted line position, and the leverage and engagement between the cover and bucket thereby obtained, to act upon the cover 11 causing the same to swing upwardly to the dotted line position, as indicated. On release of the foot pedal, the bucket is automatically lowered, and the cover of the can assumes a tightly closed position.

In the above, it will be seen that the present invention contemplates a simple and practical receptacle having relatively few parts which may be inexpensively manufactured and assembled, and, while particularly applicable as a garbage or trash can may, as above stated, be applied to other purposes where sanitation is desired.

In view of the above, it will be seen that the several objects of the invention are achieved and other advantageous results attained. As many changes could be made in carrying out the above construction, without departing from the scope of the invention, it is intended that all matter contained in the above description or shown in the ac-

companying drawings shall be interpreted as illustrative and not in a limiting sense.

I claim:

1. In an apparatus of the character described, in combination, inner and outer receptacles, one of which is movable relatively to the other, a single closure for said receptacles, means for raising the inner receptacle whereby it cooperates with the under surface of the closure to automatically raise the same, said means comprising a foot lever, a member carried by one end of said lever engaging the under side of the inner receptacle, and a reinforcing member extending across the under side of the outer receptacle for supporting the inner receptacle, and thru which said first named member is disposed.

2. In an apparatus of the character described, in combination, a receptacle, a relatively flat cover hinged to the upper part thereof, a reinforcing bridge member extending across the lower part of said receptacle, a pivotally mounted lever, a T-shaped member carried thereby and normally resting upon the upper surface of said bridge member and adapted to be raised therefrom when the opposite end of said lever is depressed, and a receptacle normally resting on said bridge member and adapted to be raised by said T-shaped member when said lever is actuated, thereby to automatically raise the cover to permit access to said last named receptacle.

LEWIS A. MARCUS.
